UNITED STATES PATENT OFFICE.

ALFRED GUMPERZ, OF BERLIN-SCHONEBERG, GERMANY.

SELF-SHAPING INCANDESCENT MANTLE FOR UPRIGHT GAS BURNERS.

Application filed February 4, 1924. Serial No. 690,640.

To all whom it may concern:

Be it known that I, ALFRED GUMPERZ, citizen of the German Empire, residing at Berlin-Schoneberg, Badenschestrasse 10, 5 Germany, have invented certain new and useful Improvements in Self-Shaping Incandescent Mantles for Upright Gas Burners, of which the following is a specification.

This invention relates to self shaping incandescent mantles for upright gas-burners.

Self forming incandescent mantles for inverted gas-burners are known, which are packed and shipped in a flat folded form not yet incinerated the incineration of which is 15 effected after attaching said mantles to the carrying ring or the burner nozzle proper, and which mantles will automatically shape and harden while being incinerated. With up-right gas-burners in which the gas flows

20 out in an upward direction, it was not possible to make self shaping incandescent mantles of any suitable form, such as would be burnt off the cellulose skeleton by the user himself and which mantles could be packed,

25 folded or flattened for transport in an incinerated state. If the user endeavors to burn the soft incandescent mantles on a common burner it will happen that already during ignition of the fabric, the mantle 30 will stick to the edge of the burner-head, and that at the same moment in which the cellulose is burnt off and the shrinking of the mantle commences, the latter will become torn during shrinkage in consequence of the

35 tension to which said incandescent mantle sticking to the head of the burner and fixed with its upper end by an asbestos thread or crook-shaped wire to the point of elevation of the carrying device is subjected.

40 It was observed that if due provision is made for shrinkage of the web in adjusting the length of the un-incinerated mantle, and such mantle is provided at its lower edge with a metal ring of thin sheet metal,

45 which ring is of such shape that it will loosely and without friction engage the head of the burner by means of a flanged edge or teeth or the like, in such a manner that the lower edge of the mantle engaged

50 thereby will not extend beyond the head of the burner, the said mantle may be incinerated without any danger of being torn on any customary burner for gaseous or liquid fuel and could be given the proper 55 shape by means of the out-flowing gases. If now the gas cock is opened, the gas al-

lowed to flow out and then ignited, the tissue will burn uniformly and commence to shrink. Then the gas cock is shut and the carbonized fabric allowed to remain for 60 some time, until the black particles of carbon attain a white colour. Thereupon the chimney is put on the burner, the gas cock opened again and the gas lit, and the mantle is allowed to shape itself under the action 65 of the gases flowing out.

The subject matter of the invention is shown in the accompanying drawing, in which—

Figure 1 illustrates a burner provided 70 with a non-incinerated incandescent mantle.

Figure 2 shows the mantle duly burnt but not shaped as yet, while

Figure 3 is a view of the mantle ready 75 shaped.

Figure 4 shows a mantle (a) with metal ring, ready for transport, and Fig. 5 shows a suitable form of the ring (b) in cross-section.

The metal ring may be substituted of 80 course by a ring consisting of a light ceramic or other suitable mass, or by a wire. Finally the mantle can be attached with its lower edge directly to the burner head by means of a wire, ribbon or an asbestos 85 thread. In that instance, however, where the connection between the burner-head and the edge of the mantle is a rigid one, especially if the latter is somewhat short and thus will shrink to a larger extent, than that 90 corresponding to the distance between the elevation point and the edge of the burner-head, the mantle will get a pointed shape or even tear. This inconvenience will be dispensed with by using a ring fitting 95 loosely on the burner-head and carried by a flange, since such ring, provided it is not too heavy, will be carried by the mantle without tearing the latter.

Now one is free to pack the soft, non-incinerated and flatly folded-up incandescent bodies together with the ring, wire or asbestos thread provided thereon, singly or in numbers for sale and the burning of the incandescent mantle may be left without hesitation to the user. Damage such as will occur in transporting the burnt incandescent bodies afterwards treated with collodion, will no longer take place. Thus transporting them is much simplified. The 110 whole work caused by burning and applying collodion to the mantles during the process

2
of manufacture is dispensed with and the price of the incandescent body is extraordinarily reduced. Moreover, no waste will occur during manufacture in the shape of 5 too narrow or too wide mantles, which will both fit badly on the burner and reduce the illuminating power of the mantles.

I claim:

1. A non-incinerated upright gas mantle 10 having suspending means at its top and a weighted lower portion for loosely surrounding the burner head, whereby said weighted portion will be free to move vertically as the mantle shrinks when burnt off.
- 15 2. A non-incinerated upright gas mantle having suspending means at its top and a weighting ring about its bottom for loosely surrounding a burner head, whereby said ring will be free to move vertically as the 20 mantle shrinks when burnt off.

3. A non-incinerated upright gas mantle having suspending means at its top and a weighted metal ring on its bottom for loosely surrounding a burner head, whereby said ring will be free to move vertically as the 25 mantle shrinks when burnt off.

4. A non-incinerated upright gas mantle having a suspending wire in its top and a weighted lower portion stiffening said portion and permitting ready adjustment onto the burner head, said weighted lower portion for loosely surrounding the burner head and free to move vertically under the shrinking action of the mantle when burnt off.

In testimony whereof I affix my signature 30 in presence of two witnesses.

DR. ALFRED GUMPERZ.
